PHOTOGRAPHIC VIEWING DEVICE

Charles A. Baratelli, Southbridge, Mass., assignor
to American Optical Company, Southbridge,
Mass., a voluntary association of Massachusetts

Application November 5, 1952, Serial No. 22,141

Term of patent 14 years

(Cl. D61—1)

To all whom it may concern:

Be it known that I, Charles A. Baratelli, citizen of the United States of America, residing at Southbridge, in the county of Worcester and State of Massachusetts, have invented a new, original, and ornamental Design for a Photographic Viewing Device, of which the following is a specification, reference being made to the accompanying drawings, forming a part thereof.

Fig. 1 is a top plan view of a photographic viewing device, showing my new design;

Fig. 2 is a side elevational view of the device turned 90° from the position shown in Fig. 1;

Fig. 3 is an end elevational view thereof taken from the left of Fig. 1; and

Fig. 4 is an elevational view thereof taken from the opposite end of Fig. 1.

The characteristic features of the design

reside in the portions shown in full lines in the drawing.

I claim:

The ornamental design for a photographic viewing device, substantially as shown and described.
